UNITED STATES PATENT OFFICE.

JOSEPH A. GROEBLI, OF NEW YORK, N. Y.

EMBROIDERING-MACHINE.

1,247,264.

Specification of Letters Patent. Patented Nov. 20, 1917.

Application filed July 9, 1915. Serial No. 39,019.

To all whom it may concern:

Be it known that I, JOSEPH A. GROEBLI, a citizen of the United States, and a resident of the city, county, and State of New York, have invented certain new and useful Improvements in Embroidering-Machines, of which the following is a specification.

The present invention relates to embroidery machines of the large type wherein the fabric is supported upon a tambour frame which is moved in a definite plane so that the needles, operating in definite paths, will pierce the fabric at different locations to form stitches arranged to constitute an embroidered design.

In such machines, it is customary to arrange a supply of fabric upon the rollers and to shift the fabric from time to time to bring new portions thereof before the needles, whereby a number of rapport rows of embroidery may be worked upon each piece of fabric.

In order to bring new portions of fabric into active position, it is necessary to release the lateral and vertical tension from the fabric, shift the fabric and then apply lateral and vertical tension thereto. In the present case, I have shown mechanism for releasing the tension, shifting the fabric and again tensioning it. Some of the mechanism herein shown is shown and described in U. S. Patent No. 1,210,793, dated January 2, 1917, and cross reference may be made to that patent for the purpose of simplifying the present case. The parts herein which correspond with parts in said case will be similarly numbered, though all such parts will not be specifically referred to herein.

The object of my present invention is to provide very simple and positive mechanical means for initiating the operation of the devices for performing the different functions in the untensioning, shifting and tensioning of the fabric. This branch of my invention is so constructed and operated that the action is positive, and the parts are not liable to become deranged or their proper automatic operation in definite order, interfered with accidentally by any action of the attendant.

Another object of my invention is to provide a very simple and efficient device for operating one fabric roller of a pair faster

than the other and for permitting the tension of the fabric to overcome the application of the operating force upon the faster moving roller while the other roller continues to operate.

Another object of my invention is to provide a very efficient fabric measuring device for determining the extent of the fabric shifting operation.

Another object is to provide automatic means for rendering the fabric measuring device inoperative while the fabric is being shifted backwardly or in a direction reverse to its automatic shifting movement.

Another object is to provide means, such as a brake, for preventing the device which renders the devices for performing different functions operative, from throwing over too far and thus initiating the several functions out of the desired sequence.

Another object of the invention is to provide for the initiation of a device for affecting the fabric by such other fabric affecting device as will produce the best results.

In the drawings forming part of this application,

Figure 1 is an elevation of an embroidery machine embodying my invention looking at the front or needle side of the machine, and in which view, the stitching devices are omitted.

Fig. 2 is a rear elevation of the tambour frame and associated parts,

Fig. 3 is a plan view of the controlling devices forming part of the present invention,

Fig. 4 is a detail view of the lateral tension device,

Fig. 5 is a sectional view, taken on the line 5—5 of Fig. 3, but with additional parts, such as the corner of the tambour frame and associated parts, added thereto,

Fig. 6 is a detail view showing, in plan, the device which co-operates with the fabric to control the shifting operation,

Fig. 7 is an elevation of the vertical tension controlling device and part of the device through which one fabric device initiates the operation of another,

Fig. 8 is a plan view thereof, with a portion of the fabric shifting controlling mechanism included,

Fig. 9 is a detail view of the support for the initiating rods,

Fig. 10 is a detail view of the block which is acted upon by the initiating rods,

Fig. 11 is a partial end elevation looking at the right hand end of Fig. 3,

Fig. 12 is an elevation of the side tension and fabric shifting controlling devices,

Fig. 13 is a detail view of the gears for connecting the initiating device shaft with the cam shaft,

Fig. 14 is a plan view of the side tension and fabric shifting controlling devices,

Fig. 15 is a sectional view, taken on the line 15—15 of Fig. 14,

Fig. 16 is a front elevation and Fig. 17 is an edge view of the trip which moves with the dial to control the fabric shifting.

Fig. 18 is a plan view of the lever which is actuated by the trip on the dial.

Fig. 24 is a detail view of a device for permitting of a slipping action of a shaft in relation to another shaft by which it is operated,

Fig. 25 is a fragmentary view showing the pawl device which appears in Fig. 24,

Fig. 26 is a detail view of the trigger resetting device,

Fig. 27 is a similar view of the same and additional parts showing them in the position when the trigger has been reset,

Fig. 28 is a detail view of the device for setting the fabric measuring device into and out of operation,

Fig. 29 is a detail view of a lever movement, and

Fig. 30 is a detail view showing the coupling between a lever and its rod.

Many of the parts herein shown are similar to those shown in my said patent, and it may be here stated that all of the mechanism shown in said patent may be used in the machine except those parts which have been superceded by others herein, if desired. But it is to be understood that the present invention is not limited in application to a machine embodying the subject of said patent.

Referring more particularly to Figs. 1, 2 and 5, it will be seen that I have shown the conventional form of embroidering machine which consists, primarily, of a rigid, stationary frame 1 consisting of end standards and longitudinal frame members. The tambour frame 2 is suspended from the rigid frame by means of a counterbalancing and parallel motion device 3 so that the tambour frame may be readily moved in any direction in a vertical plane; and, since the counterbalancing and parallel motion device and

its operation are well understood in the art, a detailed description thereof is unnecessary in this case.

The tambour frame may be operated either by a pantograph or automat and for convenience I have shown a pantograph 4 which is moved by the operator in accordance with the design held on the pattern board 5.

The tambour frame herein shown comprises the usual longitudinal and vertical bars rigidly connected to form a rectangle; and the fabric supports or rollers 16 are mounted upon the tambour frame. These rollers may, in accordance with general practice, comprise an upper roller 16 and a lower roller 16 constituting the upper pair, and an upper roller 16 and a lower roller 16 constituting the lower pair, all of which are revolvably supported on the tambour frame. A piece of fabric 16^a is stretched between each pair of rollers in position to be acted upon by the stitching devices, more or less of a supply of the fabric being wound upon one or both of the rollers.

The fabric is shifted by turning the rollers, and in the present construction I prefer to operate all the rollers from a common source. There is a longitudinal shaft 10 shown mounted in bearings on the upper part of the tambour frame and it comprises the section 10 and the section 10^a in alignment therewith, and the former is operated from a shaft 22 connected thereto at one end by a knuckle joint 23. The connections of the shaft 22 will be traced back to the source of power hereinafter.

The shaft member 10 has a worm 11 which operates a worm gear 12 on the upper end of the vertical shaft 13. The latter shaft 105 has worms 15, each of which operates a worm gear 14 on the end of a lower roller of a pair. By means of these connections the motion of the shaft section 10 in either direction is positively transmitted to the lower fabric rollers. The terms lower and upper rollers are only used to distinguish one from the other for the sake of clearness, it being understood that the operating connections might be reversed if desired; that is, the connections here described for the lower rollers might be made with the upper rollers and those described as made with the upper rollers might be made with the lower rollers.

The shaft member 10^a has a worm 11^a which acts upon a worm gear 12^a secured to the vertical shaft 13^a at the left side of the machine in Fig. 2. This latter shaft has worms 15^a which mesh with the worm gears 14 on the ends of the upper rollers of the pairs. By these connections the movement of the shaft 10^a in either direction is imparted to the upper rollers of the pairs. The worms 11^a and worm gears 12^a are of 130

greater pitch than the worms 11 and worm gears 12, in order that the upper rollers of the pairs will be revolved faster than the lower rollers except when there is a slipping 5 action as hereafter set forth. This difference in speed of the rollers is to insure some tension in the fabric while it is being shifted, so that it will not droop and wrinkle. This is made necessary by the fact that the rollers 10 at different times have relatively different quantities of fabric thereon and the diameters of the rollers and their fabric vary. The shafts 10, 10^a are driven by the shaft 22 which latter is operated by the source of power, and these two shafts 10, 10^a are made 15 relatively yieldable. For this purpose I have loosely arranged a friction disk 290 preferably made of fiber on the shaft 10^a and on the same shaft 10^a there are secured 20 two coöperating disks 291, 291^a one on each side of the friction disk 290, the disk 291^a being slidable on shaft 10^a. The disk 291^a is pressed against the friction disk 290 by a spring 292 arranged around the shaft 10^a. 25 The tension of the spring 292 may be adjusted by changing the position of the collar 293 which presses on one end of the spring, so that the yieldable action may be varied to alter the tension under which the 30 fabric is to be shifted. The friction between the disks 290, 291 and 291^a is sufficient to cause the shaft 10^a, which operates the upper rollers of the pairs, to turn these rollers until the tension upon the shifting 35 fabric reaches the desired maximum and then the shaft 10^a will slip or yield in relation to the shaft 10 until the fabric has been 40 let off the lower rollers sufficiently to permit the upper rollers to resume their movement with the fabric under the desired maximum tension.

The friction disk is driven by forked arms 290^b, secured to shaft 10, which enter notches 290^c in the periphery of the friction 45 disk 290, so that the friction disk rotates with shaft 10, although it is mounted on shaft 10^a.

In my Patent No. 1,116,693, I provided for a yieldable action, but in the present arrangement but one very simple yieldable device need be used.

There is a ratchet wheel 294 on disk 291, and there is a pawl 295 carried by the forked arm and coöperating with the ratchet wheel. 55 When the shaft 10 operates to shift the fabric from the lower to the upper roller (in the instance illustrated) the pawl 295 escapes over the teeth of the ratchet 294 and the shaft 10^a is yieldably driven through 60 the disks 290, 291. But when the shaft 10 is reversed, as when the fabric is shifted backwardly, then the pawl 295 engages a tooth of the ratchet 294 and the shaft 10^a is thus positively driven, until such time as the 65 shaft 10 is again reversed. Thus the faster

moving roller is yieldably driven in one direction and positively driven in the other.

To remove and apply the vertical tension to the fabric and to hold it true, I provide the following:

There is a longitudinal shaft 9 on the tambour frame which is operated by a shaft 21 through the knuckle joint 23. This shaft 9 has a worm 9^a which operates a worm gear 9^b on the threaded portion of a vertical 70 shaft 296 guided in a bracket on the tambour frame. The latter shaft is connected with a bar 297, which latter, as well as shaft 296 are adapted to be raised and lowered but not rotated. The bar 297 has 75 lateral arms 298 embracing the shaft 13 and these arms engage above and below the worm 15 so that, when the bar 297 is raised or lowered the shaft 13 and worms 15 are likewise raised or lowered. By this means 80 a partial rotation may be given to the lower rollers of the pairs in order to partially remove the tension from the fabric preparatory to shifting it, or in order to apply the 85 final tension to the fabric after it has been 90 shifted.

There are brackets 286 mounted upon the bar 285 which is held in the tambour frame, and the bars and brackets may be arranged at any desired intervals along the machine. The brackets 286 engage the lower rollers 16 (or the fabric wound thereon) and prevent these rollers from being drawn up out of true between their ends, and they serve the same purpose as the brackets 286 in my 100 said first mentioned patent.

There is a rod 282 which is slidable in the bracket 281 and also in an arm 288 secured to the rod 285, so that the rod 282 may be raised and lowered. The shaft 9 105 has a worm 279 which operates a worm gear 280 having a threaded connection with the rod 282. On the rod 282 there are arranged brackets 283 which engage under the upper rollers 16 (or the fabric wound 110 thereon) to hold the rollers true against the tension of the fabric, similar to the brackets 283, in my first mentioned patent. Thus the rotation of the shaft 9 will either press the brackets 283 against the upper rollers to 115 keep the rollers and fabric true, or disengage the brackets to permit the fabric to be shifted.

The lateral tension devices on the tambour frame may be the same as in my first mentioned patent. There are pressure members 154 arranged at the rear side of the machine and near the opposite edges of the fabrics. These comprise the individually yieldable rollers 154 which press on the 120 fabric and which are adapted to revolve independently of each other with the fabric. These rollers are preferably constructed and operated like the rollers 154 in my first 125 mentioned patent.

On the front side of the machine are arranged the traction or propelling rollers 152 which are carried upon the shafts 19 and the fabric is pressed against these 5 rollers by the rollers 154 so that when the former revolve they will tighten or loosen the fabric. There is a longitudinally arranged shaft 8 which is operated by a shaft 20 through the knuckle joint 23, and this 10 shaft carries worms 17 which operate on the worm gears 18 to drive the shafts 19 which carry the traction rollers.

The parts thus far described correspond with my first mentioned patent, except the 15 devices for making the drive of the fabric rollers yieldable.

Before passing from the devices associated with the tambour frame reference will be made to a portion of the fabric shifting device. At one end of the machine I have shown a roller 217 which is carried upon a shaft 214 journaled in the swinging bracket arms 215. This roller is movable into and out of contact with the fabric on the uppermost roller 16 and it preferably has a rough surface so that it will be turned by the fabric on the roller. Since it engages with the fabric and turns in accordance with the surface travel of the fabric it measures the 30 amount of fabric shifted for the purpose of automatically terminating the shifting operation. There is a spring 218 which exerts a downward pressure on the bracket arms 215 to press the roller 217 on the fabric. The shaft 299 is connected to shaft 214 by the knuckle joint 300. The bar 297 which serves to release and apply the final vertical tension on the fabric has an arm 214^a which engages under one of the bracket arms 215. 40 When the bar 297 moves downwardly to release the tension of the fabric preparatory to shifting, the arm 214^a which moves therewith allows the roller 217 to be drawn down upon the fabric roller by the spring 218. 45 When the bar 297 moves upwardly to apply the final vertical tension the arm 214^a disengages the roller 217 from the fabric. Thus the measuring roller 217 only engages the fabric while the shifting operation is 50 taking place.

As a feature of my present invention I have shown means for throwing out the measuring device when the fabric for any reason is being shifted backwardly or in the 55 reverse direction to its automatic shifting movement. This allows the fabric to be shifted backwardly without disturbing the condition of the automatic measuring device. It is preferably accomplished by 60 engaging the measuring roller from the fabric when the latter moves backwardly. I have arranged loosely on the side tension device shaft 8 a sleeve 301, which has an arm 302 having a concentric portion 303. There

is a roller 304 secured on the fabric-shifting 65 shaft 10 which engages the concentric portion 303 for the purpose of rocking it either way, according to the direction of motion of the shaft 8. There is a depending link 305 having a hook which is arranged to lift 70 the shaft 214 and measuring roller 217. When the shaft 10 operates to shift the fabric forwardly the roller 304 revolves at one end of the concentric member 303. If the fabric roller is reversed to shift the 75 fabric backwardly the roller 304 will operate to turn the concentric member 303 until the end thereof passes off or nearly off the roller. This serves to operate the link 305 and lift 80 the measuring roller from the fabric. When 85 the shaft 10 is reversed again, to shift the fabric forwardly, the roller 304 will reverse the motion of the concentric member 303 and allow the measuring roller to again engage the fabric under the action of its spring. From then on, and until the fabric is to be shifted backwardly again, the measuring device will operate as first described. The measuring device is thus automatically rendered inoperative during backward shifting 90 of the fabric. This operation in no way interferes with the automatic disengagement of the measuring roller caused by the bar 297.

The controlling devices are mounted upon 95 a bed plate 6 supported by the brackets 7. The shaft 25 corresponds with the shaft 25 of my first mentioned patent and it is provided with the same arrangement of clutches and gears. The levers and links for operating the clutches are also the same as in said case. The shaft 25 may be operated by the motor 26 through the gears 27, 28.

The shaft 22 by which the fabric shifting device is operated has a gear 31, which 105 meshes with the gears 29, 30, and this shaft is operated in one direction or another, according to whether the clutch 34 or the clutch 41 is thrown in, it being idle when both clutches are out.

The shaft 51 through which the said tension devices are operated has a gear 50 in mesh with the gears 48, 49 and this shaft is operated in one or the other direction according to whether the clutch 54 or the 115 clutch 59 is thrown in.

The shaft 67 through which the vertical tension devices are operated has a gear 66 which meshes with the gears 64, 65 and this shaft is operated in one or the other direction according to whether the clutch 70 or the clutch 74 is thrown in.

There is a block 157 threaded on the side tension device shaft 51 and it is held from 125 rotating by the rod 158 so that the turning of the shaft 51 will move the block to the right or left. There is a shaft 159 below the block, which is shiftable in the direction of

its length. This shaft 159, has a contact member 160 with which the block engages at one end of its travel and a contact member 161 threaded on the shaft 159 to be adjusted to different positions thereon. There is a three armed lever 306 fulcrumed on a pin 307 and it has one arm engaging a notched collar 308 on the shaft 159. The other arm has notches 309 to receive the spring pressed 10 catch 310 for holding the lever in either of two positions. The third arm 311 of this lever is connected with a link 312 which operates to initiate another function as will be hereinafter set forth.

15 The engagement of the block 157 with either the contact member 160 or 161 serves to shift the shaft 159 and thus move the lever 306 one way or the other. The shaft 51 has a worm 223 which operates a worm gear 224 of the fabric shifting controlling device, as will be more fully described hereinafter. Down to the lever 306 the side tension device may be the same as in my said 20 first-mentioned patent, but the gear 223 is 25 here shown mounted on the shaft 51 instead of the shaft 8.

There is a shaft 78 at right angle to the shaft 25 and it is operated step by step as the different functions are initiated, the same as 30 the corresponding shaft in my said first-mentioned patent. There is a crank 113 on the shaft 25, which operates through a pitman 114 to rock the arm 115 and on the hub of the latter there is a lever arm 118 which at certain times engages and moves a lever 122 35 having a roller 135 engaging the double cam surface of a member 136 arranged on the shaft 78. The member 136 carries an arm 137 which is provided with a pawl 138 on its outer end, which is adapted to engage the teeth of a ratchet disk 140 arranged on the shaft 78. The arm 122 which has the roller 135 is provided with a pawl 123 having an engaging projection 124. The arm 40 45 118 has shoulders 119, 120, either of which may be engaged by the part 124 according to whether the arm 118 is moving to the right or left when the pawl 123 drops.

The pawl 123 is held up out of the path 50 of the arm 118 by a crank pin 128 carried on a shaft 129. The latter has a tripping arm 130 which is adapted to be held up by a trigger 131, so that the pawl 123 will have no active engagement with the arm 118 until this trigger is tripped. When the trigger 55 is tripped and the arm 130 allowed to go down, then the shaft 129 rocks and allows the pawl 123 to fall. This will bring the projection 124 into the path of either the shoulder 119 or shoulder 120. When this engagement takes place the arm 122 will move with the arm 118 to the right or left, and the roller 135 will rock the member 136. This will operate through the pawl

138 to advance the ratchet disk 140 and the 65 shaft 78 one step which will terminate one function and initiate a succeeding one, as set forth in my said first mentioned patent.

The crank pin 128 is acted upon by the curved surface 127 of an extension 126 of 70 the lever 122 so that upon the return of the arm 122 the shaft 129 will be rocked to lift the trip arm 130 up into position where it will again be engaged by the trigger 131, 75 ready for a succeeding operation.

In order to prevent the shaft 78 from being advanced more than one step at each operation of the pawl 138 I have provided a brake for the shaft. On the shaft 78 there is fixed a brake disk 313 having eccentric 80 surfaces 314 and corresponding shoulders 319. A lever 317 fulcrumed at 318 is pulled upwardly by the spring 316 which pulls downwardly on the pawl arm 137, and the lever 317 carries a brake shoe 315 which 85 presses on the eccentric surfaces 314 to prevent the shaft 78 from moving too freely, and it also abuts against the shoulders 319 to definitely stop the shaft at each step and to hold it there during the return of the 90 pawl 138.

There is a shaft 320 which is revoluble, and also reciprocatable in the direction of its length, and one end of which is adapted to engage the trigger 131 for the purpose 95 of tripping it from the arm 130 to accomplish the above mentioned advancement of the shaft 78, whenever the shaft 320 is reciprocated.

In order to revolve the shaft 320 step by 100 step in accordance with the step by step movement of the shaft 78, I have provided a gear 321 on the latter which meshes with an intermediate gear 322; and this latter gear in turn meshes with the gear 323 on 105 the shaft 320. In this manner the shaft 320 is partially turned at every advance of the shaft 78.

The hand lever 111 by means of which the mechanism is initially started, closes a 110 switch 107 which starts the motor 26, the same as in my said first-mentioned patent. There is a cam projection 325 having a curved surface, arranged on the side of the gear 323 and on the lever 111 there is a cam projection 324 co-operating with the projection 325. When the hand lever is rocked to start the machine the projection 324 acts on the projection 325 to shift the shaft 320 and thus trip the trigger 131. This will initiate 115 the first step of the rotation of the shaft 78 and the starting of the first function. After this the tripping of the trigger will be caused automatically by the various devices.

The shaft 320 is journaled in the bracket 120 326 which holds the gears 322, 323 and also in a bracket 327. There is a spring 328 coiled around the shaft 320 and confined 125

between a pin 329 and the bracket 327, the purpose of which spring is to return the shaft 320 after it has tripped the trigger.

There are shown five different rods 330, 5 331, 332, 333, 334 slidable in holes in the bracket 327 and arranged in a circle, the sixth point of which is left blank to allow for one initiating movement to be made by the hand lever previously explained. These 10 several rods are adapted to act upon a block 335 secured to the shaft 320, for the purpose of reciprocating the latter to trip the trigger 131. This block has an abutting surface 336 which is so designed as to lie 15 in line with only one of the rods 330—334 at a time and, since the shaft 320 and block 335, are rotated step by step successively in the same direction, the rods will operate 20 successively upon the block when the arrangement of the parts is as herein shown.

The two rods 330, 334 which lie about opposite each other are fulcrumed, respectively, to the arm 336^a and the arm 337 of a lever 338 which rocks on a stud 339. The rods 331, 333 which lie about opposite each other and just above the rods 330, 335 are fulcrumed, respectively, to the arm 340 and to the arm 341 of a second lever, arranged 30 to rock on the stud 339, the arms 336^a and 337 lying above the arms 340, 341. The fifth rod 332 is connected with a member of the fabric shifting controlling device. The lever 342 has a third arm 343 to which is fulcrumed a link 344, and the latter is fulcrumed at its other end to an arm 345 on the lever 346 of the vertical tension control. The lever 338 has a third arm 347 to which 35 is fulcrumed the link 312; and the other 40 end of this link is fulcrumed to the arm 311 of a lever of the side tension controlling device.

In connection with the vertical tension control there is a rod 348 sliding in the stud 45 204 and it is fulcrumed to an arm 349 on a rocking shaft 350. The latter, as will appear, serves to lock and unlock the measuring device. The block 351 on the rod 348 is arranged to be engaged by the block 197, 50 which travels along the threaded shaft 196, when the block 197 about reaches the end of its travel in one direction.

The power for shifting the fabric is, as previously described, transmitted through 55 the shafts 22, 10, 10^a. The measuring roller 217 which is turned according to the extent the fabric is being shifted, transmits its motion through the shafts 214 and 252 to a spiral gear 222, and the latter meshes 60 with a spiral gear 221 fast on the shaft 220 of the shifting controlling device; so that the latter shaft is turned in accordance with the fabric movement. The measuring dial 226, having teeth 229 on its periphery, is

also fast on this shaft 220. The tripping 65 member 227 is held on the shaft 220 by a thumb nut 230 at any desired angular displacement with the measuring dial from a zero or starting position, with its teeth 228 engaged with the teeth of the dial 226. 70

The tripping member 227 is adapted to act upon the lever 231 in opposition to its spring 232. This lever is connected by a link 353 with an arm 354 of a lever which is loose on a shaft 355. Another arm 356 of this lever 75 is connected with the rod 332 which is one of the rods for shifting the shaft 320. When the dial 226 has been turned in accordance with the movement of the measuring roller sufficiently to bring the tripping member 80 227 into engagement with the lever 231 the latter will be rocked. This action will be transmitted through the link 353 and lever 354, 356 to the rod 332, and through the parts previously described, the shaft 78 will 85 be shifted one step to cause the ending of the fabric shifting function and the starting of a succeeding function.

There is a lever having an arm 357 and arm 358, the latter having a weight. The arm 357 90 carries a lever which is fulcrumed thereto at 359. One arm 360 of this lever is adapted to lie in a recess 239 of a disk 240 which is mounted upon the bracket 361. The arm 360 of this lever is adapted to enter the recess 239 upon the return movement of the dial, and to arrest the latter always at the same position. The other arm 362 of this lever has a double slanting surface 241 with which 95 the pin 363 on an arm 225 engages. The latter arm is loose on the shaft 220 and its hub has a worm gear 224 which is operated by a worm 225 on the shaft 51 of the side tension controlling device.

On the shaft 355 there is journaled a lever, 105 one arm 364 of which is adapted to abut against the end of the arm 357 to hold the shaft 220 and dial 226 against rotation until such time as the arm 364 is tripped. The other arm 365 of this lever is drawn in one 110 direction by a spring 366^a to engage the arm 364 with the arm 357 and it is adapted to be moved in the other direction by the lever arm 366 fixed on the shaft 350, which, as above set forth, is operated by the vertical 115 tension controlling device. The other arm 367 has a pin 368 engaging in a slot in one end of the lever 369 which has another arm 370.

The end of the arm 225 in its return move- 120 ment acts against the end of arm 370 and thereby turns shaft 350 so as to release lever 365 and permit the spring 366^a to move the lever arm 364 and lock the lever 357.

Except for the differences herein shown 125 and described the entire machine may be the same as in my said first mentioned patent and for any details not herein shown or

described with sufficient completeness reference may be made to said patent.

Operation.

5 In describing the operation it may be assumed that the fabric is in the condition just following the completion of the rapport rows of embroidery. It will be under vertical and lateral stress, and the initiating 10 device will be in the idle or zero position, the motor being at rest.

The operator will first position the tripping member 227 on the dial 226 according to the extent of the fabric is to be shifted. 15 The operator then swings the hand lever 111. This will close the switch 107 and start the motor 26. The shaft 25 and the several gears attached to it will now revolve, and the pitman 114 will rock the arm 115. The 20 throwing of the lever 111 as above described, brought the cam portion 324 on this lever into active engagement with the cam portion 325 of the gear 323 and it caused the latter and its shaft 320 to be shifted and the trigger 25 131 to be tripped. This permitted the arm 130 to fall, thus rocking the shaft 129 and allowing the pawl 123 to come into engagement with the rocking arm 118. When the pawl 123 engages one of the shoulders 30 119 or 120 the arm 122 will be moved to the right or left by the arm 118 and the roller 135 will act upon the yoke cam 136 to rock the arm 137 which carries the pawl 138. The latter will act on the ratchet wheel 140 35 and advance the shaft 78 and its associated parts one step. The arm 137 is retracted by the spring 316 which also actuates the brake device.

The first step of the shaft 78 will serve to 40 lock the lever 111 (as set forth in my said first mentioned patent) so that the motor will be continued in operation until the several functions have been performed; and it will also serve to initiate the operation 45 of the shaft 51, in the direction necessary to release the side or lateral tension devices, and this is accomplished in the same manner as set forth in my aforesaid first mentioned patent. The shaft 51 will operate through 50 the shaft 8 to first turn the traction rollers 152 in the directions necessary to loosen the lateral tension of the fabric, and at the very beginning of this operation the arms 276, which carry the pressure rollers 154, are 55 swung out to release the fabric preparatory to being shifted. While this tension releasing operation is taking place the threaded portion of the shaft 51 is moving the block 157 to the left in Figs. 12 and 14; and when 60 this block contacts with the contact member 160 it shifts the latter and its shaft sufficiently to throw the lever 306. The latter, in thus swinging, will operate through the link 312 to swing the lever 338. When the 65 shaft 78 was turned, as previously described,

upon the starting of the machine, the shaft 320 was likewise turned one step, through the gears 321, 322, 323, and this brought the block 335 from the position shown in Fig. 9 to a position in line with the rod 330. The 70 block 335 is turned in this manner each time the shaft 78 is turned a step, and in this manner it is successively brought into line with the several rods 330-334. It is to be noted that, following the tripping of the 75 trigger 131 and the falling of the arm 130, the latter was again raised into engagement with the trigger again. This was accomplished as in my aforesaid first mentioned patent, by the curved surface 127 of the extension 126 acting on the pin 128 to turn the shaft 129; thereby moving the arm 130 into engagement with the trigger and moving the pawl 123 out of engagement from the arm 118. 80

The swinging of the lever 338 in the manner above set forth, caused the rod 330 to advance against the block 335 and thus the shaft 320 was reciprocated. This tripped the trigger 131 a second time, and the shaft 78 90 is advanced a second step in the same manner as before. This advancement of the shafts 78 and 320 also advances the block 335 to bring it into line with the rod 331 by which latter alone it can then be operated. 95

This last mentioned turning of the shaft 78 terminates the unloosening of the lateral tension devices and it initiates the operation of the vertical tension devices in the direction necessary to release the vertical tension. 100

In the above-mentioned loosening of the lateral tension devices the shaft 51 of that device operated through the worm 223 and worm gear 224 to turn the arm 225 in order to bring the latter into position where it 105 can afterward return the dial device.

The second step of the shaft 78 having taken place, the lateral tension device is now idle, with the lateral tension members disengaged from the fabric and the vertical tension device 110 has commenced to operate in the direction necessary to release the vertical tension. During this last mentioned operation the shaft 196 is causing the block 197 to move to the right in Figs. 7 and 8; and when this 115 block engages the member 351 it will commence to shift the rod 348. Toward the end of this movement the rod 348 and the arm 349 will be shifted and shaft 350 will be rocked sufficiently to trip the lever 366, 367. 120 When the last mentioned action occurs, the arm 366 will act on the arm 365 so that the other arm 364 will be moved out of the path of the arm 357. The latter is now unlocked and may be turned in one direction, as will 125 later appear. From this it is apparent that the vertical tension device serves to unlock or render operative the fabric shifting controlling device during its loosening or unthreading action, and since this is the function 130

just preceding the operation of shifting the fabric the shifting device is unlocked just previous to its initiation.

The above mentioned rocking of the shaft 355 also rocked the arm 367 and as the latter engages with the arm 369 it moves the latter to turn the arm 370 and leave it in the path of the end of the arm 225 for a purpose which will appear later.

- 10 When the block 197 travels far enough to the right in Figs. 7 and 8 to engage the member 201 it will act on the latter to shift the shaft 199 and turn the lever 345. This lever will draw over the link 344 and this 15 will rock the lever 342, anti-clockwise in Fig. 8. The arm 341 of this lever will force the rod 331 against the block 335, shift the shaft 320 and thus trip the trigger 131. This will initiate the turning of shafts 20 78 and 320 another step, thus throwing the vertical tension device out of operation and the fabric shifting device into operation, and it will bring the block 335 into line with the rod 332, while, when the vertical tension 25 devices are released, that is, while the bar 297 was moved downwardly the arms 215 were allowed to move downwardly under the action of their spring 218 and the measuring roller 217 was thus brought into contact 30 with the fabric on the uppermost roller. The shifting device is now operating.

The fabric will now be shifted by the operation of the shafts 22 and 10, 10^a, acting through the worms and worm gears. The 35 upper rollers, which are receiving the fabric, operate faster than the lower rollers, so that the fabric is shifted under some tension. If this tension increases above the desired maximum then the disks 291 and 291^a will 40 slip in relation to the disk 290 and the shaft 10^a which operates the receiving rollers will remain idle until enough fabric has been released to relieve the tension, whereupon all rollers will turn.

45 During this shifting of the fabric it acts to turn the measuring roller 217 according to the extent the fabric moves. This motion is transmitted through the shafts 214 and 252 and through the spiral gears 222 and 221 to the shaft 220 which carries the dial. The dial will thus be turned until the tripping member 227 thereon acts to trip the lever 231. This lever operates through the link 353 to turn the lever 354—356 and the 55 latter in turn forces the rod 332 against the block 335 which is now in line therewith. This latter action shifts the shaft 320 to trip the trigger 131. The shafts 78 and 320 will now be advanced another step and this 60 will terminate the operation of the fabric shifting device.

If it is desired to shift the fabric a greater extent than that caused by the automatic device it may be done by manipulating the 65 hand levers in the manner set forth in my

aforesaid first mentioned patent. If, instead of shifting the fabric in the direction in which it was automatically shifted, it is shifted backwardly the measuring device will be rendered inoperative during such 70 backward operation. In that case the shaft 10 will operate in a reverse direction and the friction roller 304 will act on the sector 303 to lift the link arm 305 and by its hook lift the shaft 214 and raise the measuring 75 roller 217 from the fabric, and the latter will be held up until the shaft 10 is reversed, whereupon the roller 304 will rock the sector 303 back again and allow the measuring roller to reengage the fabric. 80

If no other shifting than the automatic one is required then the hand levers will remain as originally set, and when the fabric shifting has been completed according to the measuring device, the mechanism will continue with the next succeeding function, which will be the tightening of the vertical tension devices. 85

When the dial turned to the right in Fig. 15, in the above-described shifting operation, the lever 357 turned with it, thus carrying the lever arm 360 out of the recess 239 in the fixed plate, and while this arm 360 is held on the periphery of this fixed plate 240 the projection 241 of the arm 362 lies 95 in the circular path of the pin 363 on the arm 225.

The rod 332, as above described, pushed the block 335 and this advanced the shafts 78 and 320 and this terminated the shifting 100 operation and initiated the vertical tension devices. The latter will now operate in a direction reverse to their previous operation and this will tighten the brackets 283 and lift the worm shaft 13 to apply the vertical 105 tension to the fabric.

During this operation the block 197 will travel to the left in Figs. 7 and 8. After that the lever 345 will be thrown either by the tension of the fabric devices actuating 110 the yoke 174 to move the disk 175 against the arm 346, or else the block 197 will contact with the trip block 200 and shift the shaft 199. In either event the lever 345 will be thrown, as set forth in my said first 115 mentioned patent. The throwing of the lever 345 will be in a direction reverse to that previously described, and the link 344 and the arm 343 will throw over the lever 342. This will retract the rod 331 ready for 120 a subsequent operation and it will advance the rod 333 against the block 335 and thus the shafts 78 and 320 will be advanced another step. This will terminate the vertical tensioning operation and initiate the next function, i. e. the application of the lateral 125 tension.

The lateral tension device will now operate in a direction reverse to its previous operation. This will cause the pressure roll- 130

ers 154 to be closed against the traction rollers 152 and it will cause the latter to turn in the directions necessary to tighten the fabrics. During the tightening operation of the 5 lateral tension devices, the block 157 will travel from left to right in figures 12 and 14. When it strikes the member 161 it will shift the shaft 159 and throw the lever 306. This will act through the link 312 to throw the 10 lever 338, and as a result, the rod 330 will be retracted and the rod 334 will be advanced against the block 335. This latter operation will shift the shaft 78 and initiate the turning of shafts 78 and 320 another 15 step. It will terminate the lateral tensioning operation and also restore the mechanism to the same condition as before the hand lever 111 was thrown, and the motor and all parts of the device will remain idle 20 until the lever 111 is again turned down by the operator. The mechanism has completed all its functions. The fabric has been untensioned, shifted and retensioned.

During the above described tightening 25 operation of the lateral tension device the shaft 51 operated in the reverse direction to its first-described movement, and in so turning it operated through the worm 223 and worm gear 224 to turn back the arm 225. 30 At some point in the return movement of this arm 225 its lateral pin 363 engages one of the slanting surfaces of the extension 241, the point of engagement depending on how far the dial device moved in the shifting operation. This engagement is possible because the projection 241 is in the path of the pin 363 whenever the arm 360 is out of the slot 239, as is the case after a shifting 35 operation. After the pin 363 engages the projection 241 the lever 360 will swing around with the lever 237 until the arm 360 drops into the recess 239 and arrests its movement. At the same time, the arm 362 swings until the projection 241 is free of the 40 pin 363, whereupon the arm 225 may continue to turn without affecting the lever 357. When the arm 360 enters the recess 239 the 45 arm 357 will have passed the locking arm 364 and the latter will reengage therewith as shown in Fig. 15 and lock it in one direction.

The engagement of the locking arm 364 with the arm 357 is caused by the end of the arm 225 striking against the nose of the arm 50 370, thereby throwing the other arm 369 and the lever 366—367 in a way to disengage the latter from the inclined end of lever 365.

Having described my invention, what I claim is:

60 1. An embroidering machine having a tambour frame and fabric rollers arranged to receive the fabric one from the other, shafts arranged longitudinally of the tambour frame, one of said shafts operating the receiving roller and the other the delivery

roller, and yieldable operating means interposed between said shafts.

2. An embroidering machine having a tambour frame and fabric supporting rollers arranged in pairs and the rollers of each 70 pair being adapted to receive the fabric one from another, shafts arranged longitudinally of the tambour frame, one of which shafts operates the lower roller of each pair and the other of which shafts operates the 75 upper roller of each pair, and yieldable operating means interposed between said shafts.

3. An embroidering machine having a tambour frame and fabric rollers arranged to receive the fabric one from the other, 80 shafts arranged longitudinally of the tambour frame and adapted to operate, respectively, the receiving and delivery rollers, positive means for operating one of said shafts and yieldable means for operating 85 the other of said shafts.

4. An embroidering machine having a tambour frame and fabric rollers arranged to receive the fabric one from the other, and means for operating said rollers, including 90 means for positively operating a roller in one direction and for yieldably operating it in a reverse direction.

5. An embroidering machine having a tambour frame and fabric rollers arranged 95 to receive the fabric one from the other, and operating means therefor, comprising means for yieldably operating one roller and for positively operating the other roller, in one direction and for positively operating both 100 rollers in a reverse direction.

6. An embroidering machine having a tambour frame and fabric rollers arranged to receive the fabric one from the other, operating means therefor, including means for 105 operating one roller faster than the other and means for yieldably operating the faster roller in one direction and for positively operating it in the other direction.

7. An embroidering machine having a 110 tambour frame and fabric rollers arranged to receive the fabric one from the other, operating means therefor, including means for operating one roller faster than the other and means for yieldably operating the faster roller in one direction and for positively operating it in the other direction, and means for positively operating the slower moving roller in both directions.

8. An embroidering machine having a 120 tambour frame and fabric rollers arranged to receive the fabric one from the other, and operating means therefor, including slip- 125 pable members for operating one of the rollers in one direction and a pawl and ratchet device for causing said roller to be positively operated in the reverse direction.

9. An embroidering machine having a tambour frame, fabric rollers arranged in pairs and one roller of each pair being 130

- adapted to receive the fabric from the other of the pair, a shaft arranged longitudinally of the tambour frame and adapted to positively operate similar rollers of each pair in either direction, a second shaft arranged longitudinally of the tambour frame and adapted to operate the other roller of each pair in either direction and faster than those operated by said first shaft, slippable members for causing said second shaft to be yieldably operated by said first shaft in one direction and means for causing the second shaft to be positively operated in the reverse direction by said first shaft.
- 15 10. An embroidering machine having a tambour frame, fabric shifting means adapted to shift the fabric forwardly or backwardly, fabric measuring means for controlling the extent of the fabric shifting operation, and means for rendering the measuring device ineffective when the shifting device is operated in one direction.
- 20 11. An embroidering machine having a tambour frame, fabric shifting means adapted to shift the fabric forwardly or backwardly, and fabric measuring means for controlling the extent of the fabric shifting operation in one direction only.
- 25 12. An embroidering machine having a tambour frame, fabric shifting means adapted to shift the fabric forwardly or backwardly, fabric measuring means for controlling the extent of the fabric shifting operation, and means operated by the fabric shifting means for rendering said measuring device ineffective when operated in one direction and for restoring said measuring device when the shifting device is operated in the other direction.
- 30 13. An embroidering machine having a tambour frame, fabric shifting means adapted to shift the fabric forwardly or backwardly, fabric measuring means for controlling the extent of the fabric shifting operation, means for restoring the measuring means to a zero or starting position, and means for automatically rendering the measuring means temporarily inoperative when the shifting device is operated in one
- 35 40 45 50 55 60 65 70 75 80 85 90 95 100 105 110 115 120 125 130
- adapted to shift the fabric forwardly or backwardly, fabric measuring means for controlling the extent of the fabric shifting operation and including a roller engaging the fabric, and means for automatically disengaging said roller from the fabric when the fabric is shifted in one direction and for restoring said roller when the fabric is shifted in the other direction.
14. An embroidering machine having a tambour frame, fabric shifting means adapted to shift the fabric forwardly or backwardly, fabric measuring means for controlling the extent of the fabric shifting operation and including a roller engaging the fabric, and means for automatically disengaging said roller from the fabric when the fabric is shifted in one direction and for restoring said roller when the fabric is shifted in the other direction.
15. An embroidering machine having a tambour frame, a fabric shifting device, a vertical tension device, means for controlling the fabric shifting operation, and
- means operated by the vertical tension device for putting the said controlling device into operative condition.
16. An embroidering machine having a tambour frame, a fabric shifting device, a vertical tension device, measuring means for controlling the fabric shifting operation, locking means for the measuring means and adapted to be unlocked by said vertical tension device.
17. An embroidering machine having a tambour frame, a fabric shifting device, a vertical tension device, means for controlling the fabric shifting operation, locking means for the controlling means, and adapted to be unlocked by said vertical tension device, and means actuated by said vertical tension device for initiating the operation of the controlling device.
18. An embroidering machine having a tambour frame, a fabric shifting device, a vertical tension device, measuring means for controlling the fabric shifting operation, and locking means for the measuring means adapted to be unlocked by the vertical tension device upon its loosening operation.
19. An embroidering machine having a tambour frame, fabric shifting means, measuring means for controlling the shifting operation, manually controlled means for modifying or reversing the fabric shifting operation and automatic means for rendering the measuring means inoperative upon the reversal of the fabric shifting operation.
20. An embroidering machine having a tambour frame, fabric shifting and fabric tensioning devices, means actuated by said devices, step by step, to automatically initiate the operation of said devices, and means for arresting said step by step device.
21. An embroidering machine having a tambour frame, fabric shifting and tensioning devices, means actuated step by step by said devices to automatically initiate each other, and a brake operating on said step by step device.
22. An embroidering machine having a tambour frame, fabric shifting and tensioning devices, means actuated step by step by said devices to automatically initiate each other, and including a ratchet, a pawl for advancing the ratchet, and a brake device for arresting and stopping the ratchet and for holding it pending the reengagement of the pawl.
23. An embroidering machine having a tambour frame, fabric shifting and tensioning devices, and means for initiating the operation thereof, including a successively advanced member and mechanical means actuated by said shifting and tensioning devices and operating on said successively advanced member to control the initiating of said shifting and tensioning devices.
24. An embroidering machine having a

tambour frame, fabric shifting and tensioning devices, and means for initiating the operation thereof, including a successively advanced member and reciprocating members actuated by said shifting and tensioning devices and operating on said successively advanced member to control the initiation of said shifting and tensioning devices.

25. An embroidering machine having a tambour frame, fabric shifting and tensioning devices, and means for initiating the operation thereof, including reciprocating members actuated by said shifting and tensioning devices, means common to said reciprocating members upon which they operate, and means for bringing said common means into operative relation successively with the several reciprocating members.

26. An embroidering machine having a tambour frame, fabric shifting and tensioning devices, and means for initiating the operation thereof, including reciprocating members actuated by said shifting and tensioning devices, means common to said reciprocating members upon which they operate and means for rotating said common means step by step to bring it into operative relation successively with the several reciprocating members.

27. An embroidering machine having a tambour frame, fabric shifting and tensioning devices, and means for initiating the operation thereof, including levers having a plurality of arms, rods connected with the arms, a reciprocatable member adapted to be acted upon by said rods, means for placing said reciprocatable member successively into operative relation with said rods, said levers being actuated by said tensioning devices to advance and retract said rods.

28. An embroidering machine having a tambour frame, fabric shifting and tensioning devices, manually operated starting means, means whereby said shifting and tensioning devices may initiate each other, including reciprocating members actuated by the shifting and tensioning devices, rotative and reciprocatable means operated on by said reciprocating members, means for rotating said latter means to bring it into operative relation successively with the reciprocating members, said manually operated starting device being adapted to act upon said rotative and reciprocatable means.

Signed at the city, county and State of New York, this 7th day of July, 1915.

JOSEPH A. GROEBLI.
